UNITED STATES PATENT OFFICE.

FORREST G. PURINTON, OF WATERBURY, CONNECTICUT, ASSIGNOR TO THE PATENT
BUTTON COMPANY, OF WATERBURY, CONNECTICUT, A CORPORATION OF CON-
NECTICUT.

METHOD OF CLEANING FLEXIBLE FORAMINOUS SHEETS.

Application filed November 21, 1927. Serial No. 234,870.

This invention relates to a method of cleaning soluble material and particularly soluble solid coatings from the surface of a flexible sheet of foraminous or reticulated material. 5
More particularly the invention relates to improvements in the method of cleaning a coating of soluble material, such as pyroxylin, paint, lacquer or, particularly, the coating composition commercially known as "Duco" 10
coating from a reticulated wire screen which has been used to support articles during the painting or coating thereof by an air brush, or other spraying device, and for salvaging the coating material. 15
The invention is particularly adapted to be employed for the cleaning of screens of a button coating machine such as that disclosed in my prior application Serial No. 153,512 filed December 9, 1926. The machine disclosed in that application comprises a hopper 20
to contain a mass of buttons, or like articles, having differing obverse and reverse faces, with means for assembling articles in closely separated juxtaposition, with like faces exposed, and means for transferring such articles in their assembled position to an endless screen which passes through a painting field in which a coating of "Duco", or other suitable liquid material, is applied to the 25
articles, and which endless screen thence passes through a drier in which the volatile solvent of the coating is vaporized and removed and the dried articles thereafter deposited in a suitable receptacle. In the course 30
of time the coating material deposited upon the traveling endless screen by the painting mechanism, and baked thereupon by the drier, partially or wholly fills many of the meshes of the screen, thus interfering with 35
the proper painting of the articles by obstructing the passages through which the paint not deposited upon the articles is intended to pass and causing an undesirable accumulation of coating material upon the 40
screen which is likely to cause the buttons, or other articles, to adhere to it and also to cause undesirable accumulation of coating in the eyes of the buttons. Such screens may be quickly and economically cleaned by the 45
method and apparatus forming the subject matter of this invention and the coating material carried by the screen salvaged. 50

The present method broadly stated com-

prises rolling the foraminous sheet into the form of a scroll, rotating the scroll and subjecting the same to the action of a solvent for the soluble material carried by the sheet. 55
Desirably the scroll is rotated continuously about its axis in a bath of liquid solvent for the material in such a manner as to subject all portions of the surface of the sheet to the action of the solvent and to maintain a continuous agitation of the solvent. 60
Desirably the solvent is subjected to the influence of a force rotating in the same direction as that of the scroll to cause the liquid, in its effort to maintain its level, to flow in directions transversely of the axis of the scroll, thereby flowing upon the several spirals of 65
the sheet and through the perforations therein so that all of the surfaces of the sheet and the coating thereupon are subjected to the action of the solvent. Furthermore, the solvent is so agitated that stratification of any portion thereof, which otherwise might become a saturated solution, is avoided. 70

The rotating force acting upon the liquid solvent may be conveniently applied by enclosing the solvent in a cylindrical rotating drum or barrel and introducing the foraminous sheet, when rolled into the form of a cylindrical scroll, into the barrel so that its periphery rests upon the inner surface of the barrel, and then rotating the barrel. 75
The rotation of the barrel will rotate the scroll by reason of its frictional contact with the periphery of the scroll and the friction and adhesion between the liquid solvent and the inner face of the wall of the barrel will in effect cause the application of a rotative force to the liquid solvent which will tend to rotate the body of solvent in the same direction as the direction of rotation of the screen. 80
This rotative force carries the liquid of the solvent upwardly along the barrel at one side 85
of the axis so that the liquid in its tendency to seek its level will flow downwardly in directions transversely of the axis of the scroll and through the perforations therein, thereby subjecting the entire surface of the sheet 90
and the walls of the apertures therethrough to the solvent so that any coating material which may be adherent to the sheet will be removed by the action of the solvent. Desirably the drum is rotated with sufficient 95
rapidity to cause more or less cascading of 100
105

the solvent upon the screen so that the impingement of the liquid upon the coating will more readily dissolve it.

The preferred form of apparatus for performing the method herein described is illustrated in the accompanying drawings, in which,

Fig. 1 is an end view of a barrel containing a solvent for the coating material and illustrating in dotted lines a screen rolled into the form of a scroll and means for rotating the barrel;

Fig. 2 is a side elevation of the same, a portion of the wall of the barrel being broken away to show the liquid solvent and the scroll of wire screen; and,

Fig. 3 is a detail view illustrating a convenient method of detachably securing one of the heads to the barrel.

The apparatus illustrated in the accompanying drawings comprises a drum 1 having the form of a barrel and preferably made of sheet metal. The barrel may be provided with an integral head 2 and with a detachable head 3 which, as illustrated herein, is secured upon the opposite end or head of the barrel by a divided clamping ring 4 having laterally extending flanges 5 and 6 which are connected by a screw 7 adapted when manipulated to clamp the ring upon the barrel and to permit it to be released therefrom. The clamping ring is of arcuate cross section as illustrated in Fig. 3 and is adapted at one side to engage the beveled edge 8 of the head of the barrel and at its opposite side to engage a bead 9 formed upon the end of the barrel. A sealing gasket 10 desirably is interposed between the ring and head and is firmly clamped therebetween when the ring 4 is contracted by the setting up of the screw 7.

The barrel 1 is rotatably supported upon oppositely disposed pairs of rollers 11 and 12 which are fixedly secured to shafts 13 and 14 mounted respectively in bearings 15 and 16 carried by suitable bed plates 17 and 18. The shafts 13 and 14 are extended beyond the end of the barrel and have secured to them sprocket wheels 19 and 20 which are engaged by an endless sprocket chain 21 driven from a suitable source of power (not shown). The sprocket chain passes continuously around the sprocket wheels so that the shafts 13 and 14 and the barrel-supporting rollers carried thereby are rotated in the same direction.

The head of the barrel desirably is provided with one or more handles 22 to aid in the manipulation of the barrel as well as in the removal of the detachable head.

In the operation of the device the barrel is removed from its supporting rolls and stood on its base or head 2. It is then partially filled with a liquid solvent for the material which is to be removed from the screen; for example, if a pyroxylin coating material, such as "Duco" is to be removed from the

foraminous sheet or screen, gasoline, acetone, or other suitable solvent for the material may be introduced into the barrel.

The foraminous sheet or screen to be treated is rolled into the form of a cylindrical scroll, the outer end of the sheet being secured to the scroll in such a manner that it will not spring away from it and the scroll placed in the barrel. The head 3 of the barrel is then replaced and clamped upon the barrel by the clamping ring 9. When thus assembled the barrel is placed upon its side upon the pairs of rollers 11 and 12 and rotation imparted to these rollers through the sprocket wheels and sprocket chains. The rotation thus imparted to the barrel causes the foraminous or wire screen scroll to rotate about the axis of the scroll and the adhesion and friction between the wall of the barrel and the liquid causes the liquid to rise up with the ascending portion of the wall of the barrel and if the speed of rotation is sufficiently rapid causes the liquid to cascade down upon the screen. The liquid displaced from its normal level by such rotative movement tends again to seek its level and thereby flows in directions transversely with respect to the axis of the scroll. The liquid carried up along the ascending portions of the converging ends of the barrel will tend to flow toward the longitudinal center of the barrel to a greater or less extent, thereby augmenting the flow against the outer face of the scroll, and also assisting in agitating the solvent.

The rotation of the screen itself within the barrel serves also to agitate the solvent in the barrel and to carry more or less of the solvent above its normal level so that a considerable portion thereof passes through the apertures of the sheet. By virtue of the agitation of the solvent produced by the rotation of the barrel and the screen, saturation of any portion of the solvent is prevented and the entire body of solvent caused to act uniformly upon the sheet of foraminous material. By virtue of this action the foraminous or reticulated sheet is very quickly cleaned. It is then removed from the drum by merely removing the head of the drum and withdrawing the scroll which can then be unwound and again applied to the painting machine. The solvent which has been more or less saturated with the coating material may then be poured out of the barrel and again employed to make the coating mixture by the addition of sufficient coating material thereto to produce the proper consistency for use in the air brush, or other projecting device.

It will be understood that the particular apparatus disclosed herein is of an illustrative character, and that other forms of apparatus may be employed in the performance of the method herein described, and that

such modifications in the method and apparatus may be made as will fall within the scope and meaning of the following claims.

Having thus described the invention, what is claimed as new, and desired to be secured by Letters Patent, is:

- 5 1. The method of cleaning soluble material from a flexible foraminous sheet which comprises rolling said sheet into the form of a scroll, rotating said scroll and subjecting said scroll to the action of a moving liquid solvent for said material.
- 10 2. The method of cleaning soluble material from a flexible foraminous sheet which comprises rolling said sheet into the form of a scroll, continuously rotating said scroll about its axis in a bath of a liquid solvent for said material to subject all portions of the surface of said sheet to the action of the solvent and to maintain continuous agitation of the solvent.
- 15 3. The method of cleaning soluble mate-
- rial from a flexible foraminous sheet which consists in rolling said sheet into the form of a scroll, partially immersing the scroll in 25 a bath of liquid solvent for the material, rotating said scroll about its axis and subjecting said liquid solvent to the influence of a force rotating in the same direction as that of the scroll to cause the liquid to flow upon and 30 through the foraminous sheet in directions transversely of the axis of the scroll.
4. The method of cleaning a soluble coating from a wire screen which comprises rolling the screen longitudinally into the form 35 of a scroll, partially immersing the scroll in a bath of liquid solvent for said coating, continuously rotating the scroll about its axis and causing the solvent to cascade upon the scroll.

In testimony whereof, I have signed my name to this specification.

FORREST G. PURINTON.
